COLLAPSIBLE DRAPED PARTITION

Vernon F. Walter, New York, N. Y., and Morris Lange, Cleveland Heights, Ohio, assignors to The Superior Funeral Supply Company, Cleveland, Ohio

Application May 24, 1939, Serial No. 275,414

2 Claims. (Cl. 45—106)

This invention relates to supports for curtains and particularly to the collapsible or folding framework therein suitable for carrying drapes used as backgrounds for caskets and the like.

The principal object of the invention is to provide a framework and an attached curtain that will fold into a carrying case, which case also serves as a supporting base for the framework.

Another object of the invention is to provide a device of the type mentioned which may be readily set up or taken down by one person who need not be particularly skilled in the art and also without a loss of time or other inconvenience.

A further object of the invention is to construct such device out of materials and parts which are inexpensive to manufacture or assemble, and which when collapsed is self-contained and conveniently transportable as a single compact and light-weight unit.

These and other objects and features of the invention will become apparent from a study of the following description and claims together with the accompanying drawing in which like parts are designated by like reference characters and wherein:

Figure 1 is a front view of the partition with parts removed to show construction and assembly;

Figure 2 is a side view of the frame and case-base only taken along the lines 2—2 of the Figure 1;

Figure 3 is a front view of the frame collapsed into the case-base with the cover on and with one side of the case-base cut away to show the device as it is folded;

Figure 4 is an enlarged view of a support hingedly mounted inside the case-base and tensioned therein;

Figure 5 is a side view of the Figure 4 taken along the lines 5—5 of that figure;

Figure 6 is an enlarged view of a snap-clamp of a support which keeps the support straight when opened and which prevents it from folding in the middle when upright; and

Figure 7 is a front view of the same snap-clamp taken along the lines 7—7 of the Figure 6.

Broadly this invention consists of a container, a supporting frame and a curtain hung thereon. Each of these parts will be described in detail hereinafter.

The container member, sometimes referred to herein as the case-base is simply a long case or box 10 provided with a cover 11 which is attached to the rearward side of the box 10 with the hinges 12. The forward side and ends of the container are provided with catches 13 which hold the case

10 in either the open or the closed position. The container member is also provided with simple carrying handles 14 to facilitate the transportation and handling of the device.

The longitudinal bottom 15 of the case 10, which serves as the actual base, is provided with two brackets 16, which are firmly attached to the bottom close to the ends thereof and in line with each other. These brackets 16 may be simple L shaped blocks of wood or metal and are themselves each provided with a horizontal hole suitable for engaging a rather substantial pin 17.

The two vertical support members are made of four strips of angle iron. The two lower support sections 20 are hingedly attached to the two brackets 16 or are pivotally attached thereto with the pins 17. The support sections 20 are a little shorter than the bottom base 15 and fold inwardly therein. The pins 17 are long enough to contain coil springs 18 which are held in place with nuts 19. The springs 18 are so constructed and mounted that one end of it engages the bracket 16 and the other end engages the vertical support section 20, so that the supports tend to rise and assume upright or vertical positions. This construction and assembly is clearly shown in the Figures 4 and 5.

The vertical support member lower sections 20 and upper sections 20a are folded inward and toward each other as indicated in the Figure 1; and in order to keep them in a perfectly straight, upright and parallel arrangement, the central hinge portions or pivots 21 are provided with snap-catches 22, which automatically engage when the sections 20 and 20a are in line. A tensioned finger or trigger release 23 permits the sections to be again folded when the knob 24 is raised. The pivot and trigger release construction is clearly illustrated in the Figures 6 and 7.

The top horizontal piece referred to herein as the bridge member has a cross-bar 27 made of angle iron strips similar to the vertical sections and which may be shaped to conform to the configuration or design of the partition. The bridge member has two vertical portions 28 integral therewith which are each pivotally connected to the top ends of the vertical supports 20a. The cross-bar 27 is slightly shorter than the bottom base 15 and fits in the container when the vertical support members are completely folded.

Mounted on the vertical portions 28 of the bridge member there are two arms 30 which are swivelly connected thereto by the pins 31 through the brackets 32. The arms 30 are slightly shorter than the bottom base 15 and are foldable in the

5 container parts 10 and 11 respectively along with the supports 20 and 20a and cross-bar 27. The arms 30 are supported so as to open or swing laterally and may be curved or shaped as desired to conform to the design of the draped curtain and they are temporarily secured in position with the wing nuts 33 on the pins 31.

10 The drape or curtain 35 is made of a non-crushable or wrinkle proof fabric of which there are many kinds on the market. The curtain 35 is made in two sections, left and right. The drawing shows the right section only; the left section being the same size and shape except in reverse formation.

15 15 The extreme right and left side portions 35a have a horizontal hem at their top edges which receive the arms 30. The more central portions have simple tabs 38 at their top edges, secured with conventional snap fasteners 39 which are looped around the cross-bar 27 for their support.

20 The two halves of the curtain 35 are fastened together, after being mounted on the frame, with the fasteners 39a on their inside vertical edges and are suspended so as to completely cover the entire metal frame and container from front view.

25 The important advantages of the instant invention over similar devices in the art, are that the article is always completely assembled and 30 is always self-contained. There is nothing to remove, to take apart or to add for either folding or erection. Therefore, there is no likelihood of parts being misplaced, forgotten or lost. The parts last longer, especially the draped curtain 35 because it is always packed and unpacked in the same way, thus minimizing wear and tear.

30 It is almost automatic in its operation because of the action of the springs 18 which tend to open the frame the moment the cover 11 is turned back. In opening the device all the operator need do is to adjust or position the arms 30 as desired at the brackets 32. Upon closing the device the arms 30 are folded inward and under the cross-bar 27; the snap-catches are released and the frame is folded into the box, and

the curtain 35 folded into the container base as the frame is collapsed.

It will now be clear that there is provided by this invention a collapsible draped partition which accomplishes the objects of the invention. While the invention has been described and shown in its preferred form and while certain general terms have been used, it is to be understood that the embodiment of the invention as described is suggestive only and is not to be considered in a limiting sense. It is to be further understood that there may be other forms or adaptations of the invention and those modifications are also considered to be within the broad scope of the invention as no limitations upon it are intended other than those imposed thereon by the scope of the appended claims.

We claim:

1. A background for burial caskets, including a case, a collapsible frame receivable in the case, and connected thereto, and having a top member, an arm pivoted to each side portion of the frame adjacent its upper end and movable in one position to form a continuation of the top of the frame and to lie in the same vertical plane therewith, and in a second position to lie substantially parallel to the frame so as to be foldable therewith and received in the case, means to rigidly secure each arm in adjusted position, and curtains supported by and covering the frame and arms, the lower ends of each of the curtains being free and freely movable into and out of the case, whereby in use to provide for their disposition over the front of the case thereby to conceal the latter, said curtains having their adjacent sides formed to overlap and in said first position of the arms lying in the same vertical plane, whereby to impart the appearance of a continuous effect.

2. A background for burial caskets in accordance with claim 1, wherein the arms are mounted to substantially underlie the top member in folded position thereof.

VERNON F. WALTER.
MORRIS LANGE.
